UNITED STATES PATENT OFFICE.

JOHN E. PREST, OF WORCESTER, MASSACHUSETTS.

THREAD-BOARD FOR SPINNING-FRAMES.

No. 817,273.

Specification of Letters Patent.

Patented April 10, 1906.

Application filed June 28, 1905. Serial No. 267,381.

To all whom it may concern:

Be it known that I, JOHN E. PREST, a citizen of the United States, residing at Worcester, county of Worcester, and State of Massachusetts, have invented an Improvement in Thread-Boards for Spinning-Frames, of which the following description, in connection with the accompanying drawings, is a specification, like letters on the drawings representing like parts.

This invention relates to the thread-board of spinning and twisting machines wherein it is essential that the thread-guide holders may be raised independently each of the other when desired or may be raised all together for doffing and other purposes.

The object of the invention is to provide a simple, strong, and efficient construction of parts with provision for adjustment and so arranged that the thread-guide holders will not be tipped out of place accidentally.

The nature of the invention will more fully appear from the following description and will be set forth more particularly in the appended claims.

The drawings represent a section of a thread-board showing a section of the apparatus which will be of a length to correspond with the spinning or twisting machine.

Figure 1 is a top plan view of a portion of the roller-beam with a portion of the devices for making the present invention applied thereto. Fig. 2 represents a front elevation, with the thread-guide holders and lifting-bar elevated, of a section of the apparatus shown in Fig. 1; and Fig. 3 is a view in cross-section on the line *x* *x* of Fig. 1. Fig. 4 is a cross-section on line *y* *y*, Fig. 1.

The usual roller-beam and spinning-frame is represented at *A*. In front of this beam and attached thereto in any suitable manner, as by bolts *C*, are a series of bearings *D*, which should be sufficient in number to support the parts on the apparatus. As shown, there is one bearing for every four thread-guide holders; but under ordinary circumstances the proportion may be greater. A rod *E* is mounted in the bearings *D* and extends the entire length of the roller-beam and should be so positioned as to come quite close to the face of the roller-beam *A*.

The thread-guide holders *F* are formed of sheet metal with downturned edges *F'*, whereby rigidity of construction is secured, and have mounted at the forward end the usual thread-guide eyes *G*, a suitable adjust-

ment for the thread-guide eyes in the holders being provided and herein shown as consisting of a channeled guard-plate *g*, fitting over the bent end *g'* of the guide-eye and clamping the guide-eye in position by means of a bolt *g''*. The rear end of each thread-guide holder is provided with a plurality (here shown as two) of hinged loops *H*, which may be formed from the metal of the thread-guide holder or on an independent hinged piece bolted thereto, as at *h*. These hinged loops fit over the rod *E*, whereby each thread-guide holder is independently journaled upon the same axis. A lifting-bar *K* is mounted beneath the thread-guide holders and parallel with the rod. Preferably it is mounted by direct connection to the rod, and for this purpose a series of yokes *L* are provided, one for each thread-guide holder, except where the bearings *D* are located. These yokes are clamped to the lifting-bar in a suitable manner, as by a bolt *L''*.

The bearings *D* and the yokes *L* are located, respectively, between the hinged loops *H* of the thread-guide holders, so that the thread-guide holders are held in definite position longitudinally of the roller-beam.

An adjustment is provided whereby the thread-guide holders may be positioned properly with respect to the spindle or other device, and this consists of slotting the bearings *D* where they are bolted to the roller-beam, so that they can be moved longitudinally of the roller-beam, and also slotting the yokes *L* where they are bolted to the lifting-bar *K*, where they may be moved laterally of the lifting-bar. In this manner each thread-guide holder may be adjusted to the desired amount, which in all cases is comparatively slight.

A stop *D''* is provided on each bearing *D*, which limits the downward motion of the lifting-bar *K*. Hence the lifting-bar *K* serves to hold the thread-guide holders in their normal operative position.

It will thus be seen that in operation any thread-guide holder may be tipped up independently of the other on the rod *E*, and when it is desired to lift the entire series all that is necessary is to raise the lifting-bar *K*, for which purpose a simple lever or handle *K''* is provided, and thereupon the entire series will be thrown upward.

Having fully described my invention, what I claim as new, and desire to secure by Letters Patent, is—

1. In a machine of the character described, 35
bearings adapted to be attached to the roller-
beam, a rod sustained in said bearings, a se-
ries of thread-guide holders hinged on said
rod, a lifting-bar mounted beneath said hold-
ers and parallel with said rod, whereby indi-
vidual holders may be swung upward on said
rod, and the entire series may be swung up-
ward on said rod by raising said lifting-bar.
5 2. In a machine of the character described,
bearings adapted to be attached to the roller-
beam, a rod sustained in said bearings, a se-
ries of thread-guide holders hinged on said
rod, a lifting-bar beneath said holders and
fulcrumed on said rod whereby individual
holders may be swung upward on said rod,
and the entire series may be swung upward
on said rod by raising said lifting-bar.
10 3. In a machine of the character described,
bearings adapted to be attached to the roller-
beam, a rod sustained in said bearings, a se-
ries of thread-guide holders hinged on said
rod, a lifting-bar mounted beneath said hold-
ers and parallel with said rod, whereby indi-
vidual holders may be swung upward on said
rod, and the entire series may be swung up-
ward on said rod by raising said lifting-bar, a
stop to limit the downward movement of said
lifting-bar, causing the lifting-bar to main-
tain the holders in operative position.
15 4. In a machine of the character described,
bearings adapted to be mounted on the roller-
beam, a rod sustained in said bearings, a se-
ries of thread-guide holders, each presenting
separated hinged loops embracing said rod, a 35
lifting-bar, a series of yokes mounted on said
lifting-bar and embracing said rod between
said hinged loops, a stop to limit the down-
ward movement of said lifting-bar.
5 5. In a machine of the character described, 40
bearings adapted to be longitudinally adjust-
ably mounted on the roller-beam, a rod sus-
tained in said bearings, a series of thread-
guide holders, each presenting separated
hinged loops embracing said rod, a lifting- 45
bar, a series of yokes mounted and longitudi-
nally adjustable on said lifting-bar and em-
bracing said rod betyween said hinged loops, a
stop to limit the downward movement of said
lifting-bar.
50 6. In a machine of the character described,
a series of bearings adapted to be adjustably
mounted on the roller-beam, a rod sustained
in said bearings, a lifting-bar having a series of
yokes adjustably mounted on and embracing 55
said rod, a series of thread-guide holders,
each provided with two separated hinged
loops embracing said rod and adapted to span
one of the said bearings or one of the said
yokes, a stop to limit the downward swinging 60
movement of said lifting-bar.

In testimony whereof I have signed my
name to this specification in the presence of
two subscribing witnesses.

JOHN E. PREST.
